(57) **CLAIM**

The ornamental design for a terminal for a tablet press, as shown and described.

DESCRIPTION

FIG. 1 is a front perspective view of a terminal for a tablet press, illustrating the new design in accordance with an embodiment;

FIG. 2 is a front facing view thereof;

FIG. 3 is a left side view thereof;

FIG. 4 is a right side view thereof;

FIG. 5 is a rear facing view thereof;

FIG. 6 is a bottom view thereof; and,

FIG. 7 is a top plan view thereof.

Broken lines as shown in the accompanying drawings illustrate a use environment, but do not form a part of the claimed design.
